UNITED STATES PATENT OFFICE.

GEORGE HAROLD EATON, OF SHEFFIELD, ENGLAND, ASSIGNOR OF ONE-HALF TO HERBERT TERRY & SONS, LIMITED, OF REDDITCH, WORCESTERSHIRE, ENGLAND.

MEANS FOR CLEARING GLASS WINDSCREENS AND THE LIKE.

Application filed April 1, 1924. Serial No. 703,443.

To all whom it may concern:

Be it known that I, GEORGE HAROLD EATON, a subject of the King of Great Britain, residing at 29 Montgomery Road, 5 Sheffield, England, have invented Improvements in or Relating to Means for Clearing Glass Windscreens and the like (for which I have filed an application in Great Britain on March 19, 1923, under No. 7,789), of 10 which the following is a specification.

This invention is for improvements in or relating to a device for clearing the windscreens of vehicles, and more particularly to a device of the type comprising an outer 15 wiper, adapted to engage with the outer surface of a transparent windscreens, and means whereby the wiper may be pressed into engagement with the surface of the windscreens.

The present invention consists of a device 20 of the type referred to for clearing the windscreens of vehicles and the like in which the outer wiper comprises a substantially flat element built up of a plurality of superimposed strips of textile material the ends of 25 which are adapted to be detachably secured upon a longitudinal holder.

Further, the present invention consists of a device for clearing the windscreens of vehicles as set forth in the preceding paragraph, wherein the holder is formed of substantially U cross section so as to permit the 30 ends of the superimposed strips of material to be folded over the ends of the holder so as to lie between the parallel limbs thereof, and engage with means for clamping the 35 ends of the said material to the said holder.

The invention is more particularly described with reference to the accompanying drawing, in which:—

40 Figure 1 illustrates in elevation one method of carrying the invention into effect.

Figure 2 is a side elevation of Figure 1.

Figure 3 is a plan view on the line A—A of Figure 1, and

45 Figure 4 is a modified construction of the said device.

Referring to the drawings, 1 comprises an arm constructed of substantially U-shaped formation. The arm 1 is provided 50 at each end with a bridge-piece 2 carried upon trunnions 3 which are mounted in bearings 4 in the side walls of the arm 1. The bridge-piece 2 is arranged to carry a screw-threaded stem 5, which is provided 55 at the end adjacent to the base of the

U-shaped arm 1 with a base-piece 6, and provided at its free end with a milled head 7. The side walls of the arm 1 are extended slightly beyond the base thereof, and the arm is adapted to receive a plurality of 60 superimposed layers 8 of a textile material, such as linen and these layers are held in position on the arm 1 by folding back the ends of the said layers between the arms of the U-shaped member 1 into a position 65 in which they may be clamped between the base-piece 6 and the base of the arm 1.

Mounted adjacent to the arm 1 is a back-support 9, which is substantially of U-shaped cross-section, and is adapted to receive a rubber or like pad 10, whereby mist may be removed from the inner surface of the screen. Fitted to the back of the back-support 9 is a spring 11, which is arranged 70 to extend upwardly and over one end of 75 the arm 1, and then downwardly into engagement with the base of the said arm, and the said spring is held in position on the said arm against lateral movement by means of the upright limbs of the said 80 arm, and the said spring is restricted in its movement transversely to the base of the said arm by lateral projections 11^a formed on the upright limbs thereof, which 85 projections overlie the free end 11^b of the said spring.

The free end of the said spring has a bulge formed therein, which is adapted to engage with one of a number of holes or indentations 1^a formed in the base of the 90 arm, so as to enable the said arm to be held in a definite predetermined position relatively to the said spring. Formed on the back of the back-support 9 is a handle 12, which handle may be formed integral with 95 the spring 11, or independent thereof.

Referring to Figure 4, there is illustrated in perspective a device similar to that hereinbefore described with the exception that in this example the superimposed layers 8 100 are bifurcated at their ends so as to enable them to be slipped past a screw-threaded stem 13 mounted on the arm 1 and arranged to receive a plate 14, by which the layers 8 105 are clamped firmly in position, once the screw 15 has been tightened upon the screw-threaded stem 13.

Thus it will be seen that if a windscreens 110 is clamped between the said wiper arm and the back-support, with the superimposed

layers of the arm in contact with the forward surface of the windscreens, the occupant of a motor vehicle, may, by means of the handle 12, rub the device backwards and forwards over the surface of the windscreens, and thereby clear the external surface thereof.

Although it will be found that a wiper constructed in the manner hereinbefore described may be extremely effective in removing rain-drops and the like from a windscreens, nevertheless, it is desirable to prevent the formation of subsequent drops on the surface cleared, and, in order to attain this object, the wiper is preferably treated with a composition such that when moistened it will leave a film on the surface of the glass of such a character as to prevent the formation of drops of water or moisture upon the surface thereof, which drops of water or moisture would undoubtedly impair the vision of the occupant of the vehicle.

A preferred composition for treating the wiper is composed of a resinous, slightly oily substance, which may be prepared by forming a saturated but clear solution of dark resin in methylated spirits, and thereafter treating the same with some such vegetable or seed oil as castor oil, in the following manner:—

To two drachms of the solution composed of resin dissolved in methylated spirits, approximately 1.4 per cent castor oil is added. This percentage is an approximation, as in practice, the amount of castor oil added constitutes a drop.

The material which constitutes the layers of the wiper is then soaked in the preparation hereinbefore referred to, and allowed to dry, whereupon the material is again soaked and dried a second time, when it is found to be in its preferred form.

Although I have specified specific proportions in which the composition for treating the wiper may be made up, nevertheless, it is to be understood that satisfactory results may be obtained with proportions of a different character.

Thus it will be seen that, according to this invention, there is provided a device for clearing a windscreens which is simple in its

construction, efficient in its operation, and inexpensive in its manufacture, and which, by reason of the fact that a surface contact rather than a line contact is provided between the screen and the wiper, a more effective wiping operation is secured. 55

Also, according to this invention, there is provided means whereby the external surface of a windscreens may be treated so as to prevent the adhesion of drops of water or moisture to the surface thereof, and it will be appreciated that although one specific method of treating a wiper has been described, many methods of a similar character will present themselves to one skilled in the art, and, consequently, I do not limit myself to the specific proportions hereinbefore enumerated. 60 65 70

What I claim as my invention and desire to secure by Letters Patent is:—

In a device for clearing the windscreens of vehicles, the combination of a straight holder of substantially U cross-section, a plurality of longitudinal cleaning strips arranged in and extending across the channel of said holder, superimposed in substantially flat formation to constitute an outer wiper and having their opposite ends infolded over the ends of the holder and lying between the forwardly upstanding parallel limbs of the holder, clamping means mounted at opposite ends of the holder and operative between said forwardly upstanding limbs to clamp said infolded ends of the strips to the holder, a back support of channel formation having its channel presented to said outer wiper, an inner wiper arranged in the channel of said back support to engage with the inner surface of the windscreens, a handle on the back of said back support, and a flexible spring arranged to straddle the windscreens and having one end attached to the upper end of the back support and the other end attached to the said holder at a point intermediate the ends thereof to press the outer wiper against the windscreens and cause it to move uniformly with the inner wiper. 75 80 85 90 95 100

In witness whereof I have hereunto set my hand.

GEORGE HAROLD EATON.
